(57) **CLAIM**

The ornamental design for a chimney cleaning apparatus, as shown and described.

DESCRIPTION

FIG. 1 is a front elevational view of a chimney cleaning apparatus showing my new design;

FIG. 2 is a side elevational view thereof;

FIG. 3 is a top plan view thereof;

FIG. 4 is a bottom plan view thereof; and,

FIG. 5 is a perspective view thereof.

The handle is shown broken away to indicate an unspecified length.
